UNITED STATES PATENT OFFICE.

SAMUEL HENRY JOHNSON, OF STRATFORD, ENGLAND.

ELECTRIC-ARC LAMP.

SPECIFICATION forming part of Letters Patent No. 691,549, dated January 21, 1902.

Application filed July 29, 1901. Serial No. 70,128. (No model.)

To all whom it may concern:

Be it known that I, SAMUEL HENRY JOHNSON, a subject of the King of England, residing at Stratford, county of Essex, England, 5 have invented certain new and useful Improvements in or Relating to Electric-Arc Lamps, (for which I have made application for Letters Patent in Great Britain under No. 11,135, dated May 30, 1901,) of which the following is a specification.

This invention relates to improvements in electric-arc lamps, and has particular reference to lamps of the type in which the regulation of the arc is effected by means of a 15 thermo-expansive metallic strip through which the current passes. Many attempts have been made to construct arc-lamps of this kind; but such lamps have hitherto been unsuccessful for various reasons, among which 20 may be mentioned the absence of any arrangement whereby a regular or step-by-step feeding of the movable carbon could be obtained, the frequent stoppage of the arc through the carbons not coming into contact 25 automatically after the current had been broken, and the fact that the lamps were generally designed so that the feeding-point corresponded to the striking rather than to the working position of the carbons.

30 In arc-lamps according to this invention, as is generally the case in lamps of the type mentioned, the thermo-expansive strip is connected to a spring-controlled lever operating a slip-clutch encircling the upper carbon or carbon-holder. The object of this invention, however, is to introduce features 35 which obviate the disadvantages above mentioned and make the lamp efficient and reliable without rendering it unduly complicated.

40 In order that the feeding action shall be regular, I provide an auxiliary clutch, preferably encircling the upper carbon above the ordinary clutch, and to insure that the carbons shall always return into contact with each other when the current is broken the distance between the lower clutch and the end of the spring-controlled lever to which it is linked is a variable one. A link or other connection is provided between the auxiliary clutch and the spring-controlled lever, so that movement of the latter due to the contraction

of the strip when the current ceases trips the auxiliary clutch. In order that the feeding-point of the lamp shall correspond to the 55 working positions of the carbons rather than to their striking positions, a tripping-lever or the like is provided, which automatically comes into action after the arch has been struck.

In order that my invention may be clearly 60 understood and readily carried into effect, I shall proceed to describe the same fully, with reference to the accompanying drawings, in which—

Figure 1 is a side elevation of a lamp fitted 65 with clutch mechanism according to this invention. Fig. 2 is a side elevation of the lamp-bracket with a portion of the supporting-arm. Figs. 3, 4, and 5 are side elevations of the clutch mechanism in different positions 70 assumed when the lamp is at rest and working.

Like letters indicate like parts throughout the drawings.

In constructing the improved apparatus for regulating the arc a thermo-expansive strip 75 A is connected to a lever B, controlled by a spring B', operating a slip-clutch B², encircling the upper carbon or carbon-holder C. I further provide an auxiliary clutch D², encircling the upper carbon C above the ordinary clutch B². The upper clutch D² is suspended from a lever D, having a counter-weight D' and provided with stops on each side E E', so that the lever D has a limited motion proportional to the space through 85 which the upper carbon C is moved at each step of the feed.

The connecting-link between the lower clutch B² and the end of the spring-controlled lever B consists of a pin F, passing freely 90 through a hole in the clutch and provided with a head to prevent its withdrawal.

A projection D³ is fitted to the upper clutch D², so that the movement of the spring-controlled lever B due to the expansion of the strip A when the current increases trips and releases the upper clutch D, then pushes it into a new and higher position on the upper carbon, limited to the preadjusted feed by the stop E, as shown in dotted lines in Fig. 4. 100

In order that the feeding-point of the lamp shall correspond to the working position of the carbons, a tripping-lever G is provided, having a projection G', which automatically

swings beneath the lower clutch B^2 after the arc has been struck. This lever G is pivoted at G^2 and carried on the clutch-guide standard H, attached to the casting forming the upper-carbon guide. The lever G is also provided with a finger G^3 , which is engaged by the lever B as it falls when the current is cut off, Fig. 5.

The tailpiece D⁴ of the upper clutch D² is provided with a link J, through which the lever B passes, in order that the movement of the latter due to the contraction of the strip A when the current ceases may trip the upper clutch D², Fig. 5.

15 The lever B, which is actuated by the strip A, is pivoted at B^3 and is provided with a vise A', which grips one end of the strip A. The terminal of the lead K which conveys the current to the upper carbon C is attached, 20 by means of the binding-screw L, to the other end of the thermo-expansive strip A, and an adjusting-screw M is also provided for the strip A. The initial position of the lever B can be adjusted by means of the screw M', 25 which engages the end of the spring B'. Insulators N support the strip where necessary, and insulation N' is also provided at other points. Contact between the lever B and upper carbon C is made by the short flexible 30 connection O and carbon-contact P. The other terminal is connected through the vertical rod Q and casting Q', forming the lower-carbon holder of the lamp.

35 The globe R of the lamp is rendered easily and safely removable by placing asbestos washers R² in the globe-rests R', the lower rest being in form of a collar supported on a coiled spring R³.

40 To explain the operation of the mechanism above described in regulating the feed of the lamp, it will be advantageous to describe what takes place from the time of switching on the current to the lamp. When the mechanism is at rest before the current is turned on, as 45 illustrated in Fig. 3, the lower clutch B² will be resting on the clutch-rest H', and the link F will have passed through the hole in the clutch B² for some distance below the clutch-rest H'. When the lamp-circuit is completed, 50 the expansion-lever B will begin to rise, owing to the expansion of the strip A, permitting the spring B' to contract and raise the lever B and the suspension-link F. The mechanism is arranged so that when the lamp is cold the link F protrudes through the clutch B², and hence when the current is turned on the first momentary action of the expansion of the strip A is to take up what may be termed the "slack" in the link F before the 55 clutch B² is tilted to grip the carbon C, as shown by the dotted position in Fig. 3. It will be readily understood that this slack provides a margin which is sufficient to insure that however long the arc may be when the 60 current is cut off the clutch B² will reach its tripping-point and allow the upper carbon C to slip right through it into contact with the

lower one. The expansion continuing, the spring B' continues to raise the lever B, carrying with it the clutch B² and lifting the upper carbon C, thereby striking the arc. As the current continues the strip A further expands and the lever B continues to rise, during which time the clutch B² pushes the pivoted lever G out of its way until the end of 75 the clutch B² comes above the trip-table G' of the trip-lever G, which then automatically

80 swings beneath the lower clutch B², ready to trip it when required, Fig. 1. Normally the projection G' on the tripping-lever G trips the lower clutch B² for feeding the upper carbon C, so that feeding takes place at a point where the distance between the carbons is approximately the length of the arc when struck and separated to the normal working position. 85

The carbons gradually burn away, and the length of the arc becomes increased, producing a greater resistance, gradually diminishing the current passing through the thermo-expansive strip A, with the result that the 90 temperature is reduced, and owing to the consequent contraction of the strip the lever B is lowered, carrying with it the upper carbon and clutch B² until the latter is tripped on the trip-table G' of the tripping-lever G. The 95 upper carbon C is thus allowed to pass through the clutch B², but is immediately seized by the upper clutch D², so that the carbon C in dropping pulls down the upper lever D until it meets the limiting-stop E', which prevents 100 the further descent of the carbon. The slight shortening of the arc increases the current, and the thermo-expansive strip A expands, bringing the lower clutch B² into its operative position, and then the auxiliary 105 clutch D² is tripped by the end of the spring-controlled lever B coming into contact with the projection D³, which causes the upper clutch D² to take the new position higher up on the carbon, ready for the next step of the 110 feed, as illustrated in Fig. 4. When the current is broken and the expansive strip A contracts, the spring-controlled lever B, operated thereby, is brought into contact with the finger G³ on the pivoted tripping-lever G, so that 115 the projection G' is removed from under the lower clutch B², and the latter thus falls onto the clutch-rest H' in the position it occupied before the arc was struck, as shown in Fig. 5.

The carbon C is seized by the upper clutch 120 D² and falls therewith until the lever D meets the stop E', as in the ordinary process of feeding above described; but the current having 125 ceased the strip A continues to contract, so that the carbon C is suspended in the upper clutch until the lever B touches the bottom of the link J, which trips the upper clutch D², allowing the carbons to come together, Fig. 5.

The tripping-lever G might be omitted; but in that case it would be necessary to depend 130 on the clutch-rest H' for tripping the clutch B² when the feed is required. A very considerable shortening of the arc and consequent reduction in the amount of light would

then take place before the lower clutch B^2 could return to the rest H' to be tripped thereon and let the upper carbon C pass. There would consequently be a very considerable variation in the amount of light emitted by the lamp, corresponding to the distance to which the carbons might be separated.

The clutch-gears have been described and illustrated as applied to an upper carbon; but they could of course be applied to any movable carbon.

In the construction illustrated in the accompanying drawings the thermo-expansive strip A is so placed that it is not influenced by the heat of the arc, an obvious advantage when it is remembered that the action of the lamp depends upon the temperature of the strip. The strip A is placed horizontally, being supported by the insulators A' upon a bracket A^2 and arm A^3 , extending, say, from a wall, the arm A^3 carrying at its end the other portions of the lamp.

Resistance or choke coils for reducing the intensity of the current necessary for the best working of the arc would have to be employed with this lamp in the same way as is generally the case. These are not shown in the drawings, as they do not form any part of the invention.

In some cases a series of brackets holding lamps can be placed around a central tube, the expansion-strips for all the lamps being placed vertically; but it is to be understood that the invention is not confined to the particular construction mentioned and that any alterations in detail may be made to suit particular circumstances. For example, the lever B , acted upon by the expansive strip A , may be controlled by a counterweight instead of by a spring, or, again, the trip-lever G may be spring-controlled instead of being arranged to swing by gravity into its position.

What I claim as my invention, and desire to secure by Letters Patent, is—

1. In an arc-lamp the combination of means controlled by the current for regulating the carbons, a main slip-clutch on the movable carbon, a rest for disengaging the main clutch at the minimum limit of its range, a second slip-clutch encircling the movable carbon and means for tilting and tripping said clutch and allowing it only a limited motion.

2. In an arc-lamp the combination of a pivoted lever the movement of which is controlled by the current, a main slip-clutch on the movable carbon having a non-rigid connection with the lever; a rest for disengaging the main clutch at the minimum limit of its range, a second slip-clutch encircling the movable carbon and means for tilting and tripping said clutch and allowing it only a limited motion.

3. In an arc-lamp the combination of a pivoted lever the movement of which is controlled by the current, a main slip-clutch on the movable carbon having a non-rigid connection with the lever, a rest for tripping

the main clutch at the minimum limit of its range, a second slip-clutch encircling the movable carbon, means for tilting and tripping said clutch and allowing it only a limited motion and means for moving the second clutch on the movable carbon when the lever is at the maximum limit of its range.

4. In an arc-lamp the combination of a pivoted lever the movement of which is controlled by the current, a main slip-clutch on the movable carbon having a non-rigid connection with the lever, a rest for tripping the main clutch at the minimum limit of its range, a second slip-clutch encircling the movable carbon, means for tilting and tripping said clutch and allowing it only a limited motion, means for moving the second clutch on the movable carbon when the lever is at the maximum limit of its range and means for tripping the second clutch as the lever falls to the minimum limit of its range when the current is cut off.

5. In an arc-lamp the combination of a pivoted lever the movement of which is controlled by the current, a main slip-clutch on the movable carbon having a non-rigid connection with the lever, a rest for tripping the main clutch at the minimum limit of its range, a second slip-clutch encircling the movable carbon, means for tilting and tripping said clutch and allowing it only a limited motion, means for moving the second clutch on the movable carbon when the lever is at the maximum limit of its range, means for tripping the second clutch as the lever falls to the minimum limit of its range when the current is cut off and a pivoted tripping-lever adapted to engage the main clutch when the carbons exceed their normal working distance apart and adapted to be put out of action by the lever when the current is cut off.

6. In an arc-lamp the combination of a pivoted-lever the movement of which is controlled by the current, a main slip-clutch on the upper carbon having a non-rigid connection with the lever, a rest for tripping the main clutch at its lowest position and a pivoted tripping-lever adapted to engage the main clutch when the carbons exceed their normal working distance apart and adapted to be put out of action by the lever when the current is cut off.

7. In an arc-lamp the combination of a thermo-expansive strip forming a part of the circuit, a pivoted lever connected to one end of said strip, a spring adapted to raise the lever when the strip expands, a main slip-clutch on the upper carbon connected to the lever, a rest on which the main clutch trips when at its lowest position, a second slip-clutch encircling the carbon above the main clutch and normally tilted by a counterweighted pivoted lever and stops to limit the motion of the said lever.

8. In an arc-lamp the combination of a thermo-expansive strip forming a part of the circuit, a pivoted lever connected to one end

- of said strip, a spring adapted to raise the lever when the strip expands, a main slip-clutch on the upper carbon connected to the lever by a non-rigid link, a rest on which the main clutch trips when at its lowest position, a second slip-clutch encircling the carbon above the main clutch and normally tilted by a counterweighted pivoted lever and stops to limit the motion of said lever.
9. In an arc-lamp the combination of a thermo-expansive strip forming a part of the circuit, a pivoted lever connected to one end of said strip, a spring adapted to raise the lever when the strip expands, a main slip-clutch on the upper carbon connected to the lever by a non-rigid link, a rest on which the main clutch trips when at its lowest position, a second slip-clutch encircling the carbon above the main clutch and normally tilted by a counterweighted pivoted lever, stops to limit the motion of said lever and a projection on the second clutch engaging with the spring-controlled lever when in its highest position so as to trip the second clutch.
10. In an arc-lamp the combination of a thermo-expansive strip forming a part of the circuit, a pivoted lever connected to one end of said strip, a spring adapted to raise the lever when the strip expands, a main slip-clutch on the upper carbon connected to the lever by a non-rigid link, a rest on which the main clutch trips when at its lowest position, a second slip-clutch encircling the carbon above the main clutch and normally tilted by a counterweighted pivoted lever, stops to limit the motion of said lever, a projection on the second clutch engaging with the spring-controlled lever when in its highest position so as to trip the second clutch.
11. In an arc-lamp the combination of a thermo-expansive strip forming a part of the circuit a pivoted lever connected to one end

of said strip, a spring adapted to raise the lever when the strip expands, a main slip-clutch on the upper carbon connected to the lever by a non-rigid link, a rest on which the main clutch trips when at its lowest position, a second slip-clutch encircling the carbon above the main clutch and normally tilted by a counterweighted pivoted lever, stops to limit the motion of said lever, a projection on the second clutch engaging with the spring-controlled lever when in its highest position so as to trip the second clutch, a link on the tail-piece of the second clutch engaging with the spring-controlled lever when the current is cut off so as to trip the second clutch, a pivoted tripping-lever having a projection adapted to engage the main clutch when the carbons exceed their normal working distance apart and a finger on the tripping-lever engaging with the spring-controlled lever when the current is cut off to put the tripping-lever out of action.

12. In an arc-lamp the combination of a thermo-expansive strip forming a part of the circuit, a pivoted lever connected to one end of said strip, a spring adapted to raise the lever when the strip expands, a main slip-clutch on the upper carbon connected to the lever by a non-rigid link, a rest on which the main clutch trips when at its lowest position, a pivoted tripping-lever having a projection adapted to engage the main clutch when the carbons exceed their normal working distance apart and a finger on the tripping-lever engaging with the spring-controlled lever when the current is cut off to put the tripping-lever out of action.

In testimony whereof I have signed my name to this specification in the presence of two subscribing witnesses.

SAMUEL HENRY JOHNSON.
